UNITED STATES PATENT OFFICE

2,065,978

APPARATUS FOR LOADING CENTRIFUGAL EXTRACTORS

Hubert Krantz and Heinrich Buysch, Aachen,
Germany, assignors to the firm of H. Krantz,
Aachen, Germany

Application September 21, 1931, Serial No. 564,168

6 Claims. (Cl. 210—76)

This invention relates to centrifugal extractors, such as extractors for laundries, and has more particularly reference to extractors of the kind described in our application for Letters Patent Serial No. 516,471, with which the rotary basket has a detachable top rim to which is attached a permeable bag for receiving and holding the charge, the bag being adapted to be removed and replaced with the rim relatively to the basket by means of a suitable conveying and lifting device, to which the rim can be detachably connected.

The invention has for its object to provide a simple apparatus which allows of an easy and quick loading of extractors of the kind stated, this apparatus essentially consisting of a portable and rotatable frame separate from the extractor on which the detachable basket rim with the bag after having been withdrawn from the extractor and emptied, can be freely supported in such a manner that the rim can be detached from the lifting device and the bag filled with the material to be extracted at any suitable place of the working room, for instance directly adjacent to a washing machine the wet goods of which are to be treated in the extractor.

Another object of the invention is to give the said rim-and-bag supporting frame substantially the same shape as the extractor basket, so that the bag when lowered into the frame and filled with material, adopts the shape suitable for its insertion into the extractor basket, and to provide means for maintaining this shape of the filled bag while being carried to and lowered into the extractor basket.

In order to allow of the invention to be more clearly understood, it will now be described with reference to the accompanying drawings which illustrate a preferred embodiment of our apparatus. Fig. 1 is a sectional view of the portable rim-and-bag supporting frame, the bag being filled with material; Fig. 2 shows the rim and filled bag suspended from a conveying device ready for being lowered into an extractor, and Fig. 3 is a sectional view of an empty extractor ready to receive the rim and bag.

Referring to the drawings in detail, 1 is the extractor and 2 the rotary basket thereof. 3 is the bag which is made of network or of a suitable permeable fabric. 4 is the rim of the basket which is detachable from the basket shell. The bag 3 is attached by its upper end to the underside of the rim 4, while its lower end is provided with a number of eyelets through which is passed a cord 5, which can be drawn tight and

tied or untied for closing and opening the bag, respectively.

For withdrawing the rim and bag from the extractor and replacing them therein, there is used a suitable conveying device such as a crane 6 with suspension ropes 7 which are adapted to be detachably connected with the rim, as shown in Fig. 2. As the crane may be of a conventional type, only its working pulley and suspension hook are shown in the drawings.

To allow of the bag 3 to be easily and quickly filled with the material to be treated at any desired place outside the extractor, we provide a frame 8 adapted to have the rim 4 deposited on its upper edge and the bag lowered into its interior. This frame is preferably carried by a truck 9 having floor wheels 10 and a central pivot 11, about which the frame 8 can be turned; the frame has at its bottom a plate 12 with a central bore which is engaged by the pivot 11. Antifriction means 13 between the plate 12 and the truck 9 facilitate the turning of the frame on the truck. The frame 8 can easily be moved about in the working room, such as between extractors and washing machines in laundries, and when being loaded can be turned about its central vertical axis to allow proper distribution of the material in the bag 3.

The frame 8 has the contour and dimensions of the extractor basket 2. Thus, when the bag 3 is lowered into and the rim 4 deposited on the frame 8, the bag will adopt the same shape and position it is forced to take in the extractor. Many extractors have on their bottom a hollow inwardly extending conical projection, such as shown at 14 in Fig. 3, this hollow cone serving to accommodate the bearings of the basket spindle. When the apparatus according to the invention is designed to be used for loading extractors of this kind, the frame 8 is provided with a similar cone-shaped projection 15. When the bag 3 is lowered into the frame, the central portion of the closed lower end of the bag, i. e. the tied cord 5, lays on the summit of the cone 15 and the walls of the bag fit to the inner surfaces of the frame. In order to hold the filled bag in the shape it assumes in the frame 8 while it is withdrawn from this frame, carried over the extractor and lowered into the latter, the crane 6 is provided with a rope 16 which, when

the bag has been filled in the frame 8, is attached by its lower end to the cord 5 and holds same in its elevated position relatively to the bag, as shown in Fig. 2. It is attained hereby that the filled bag can be introduced smoothly

into the extractor basket so that the charge is uniformly distributed in the same.

The operation of the apparatus described is as follows: Assuming the apparatus to be used in a laundry, the portable frame 8 is positioned quite close to a washing machine and an empty bag 3 with the rim 4 received and held by the frame 8 as shown in Fig. 3, the suspension ropes of the crane being detached from the rim and bag. The wet material of the washing machine is then filled directly into the bag 3. During the filling, the frame 8 may be turned as desired to permit uniform distribution of the material in the bag. When filled, the frame 8 is moved to the extractor, whereupon the ropes 1, 16 of the crane 6 are attached to the rim 4 and cord 5, respectively. The rim with the filled bag is then withdrawn from the frame 8, brought over the extractor and then lowered into the basket, the rim 4 seating on the upper margin of the basket to which it is connected through suitable locking means. The ropes of the crane 6 are detached from the rim and bag and the extractor is started. In the meantime, the empty frame 8 is moved back to the same or another washing machine to receive another charge. Of course, instead of moving the frame from the washing machine with the full bag to the extractor, the frame may also be left near the washing machine and the rim with the filled bag carried to the extractor by the traveling crane 6. At the end of the extracting operation, the extractor is stopped; the ropes 1 are attached to the rim 4, and the rim with the bag is withdrawn from the extractor and carried to the place where it is desired to empty the bag. This is done by untying the cord 5 which, in the removal of the bag from the extractor, has not been attached to the rope 16. The bag when empty is closed by the cord 5 and then lowered again into the frame 8 or another similar frame to receive a fresh charge of material.

While the frame 8 is herein shown as consisting of a cylindrical casing, it might also be made of a number of bars and brackets sufficient to support the rim 4 in a proper position to allow of an easy filling of the bag attached to the rim.

Suitable locking means, not shown, may be used for preventing accidental turning of the frame 8 relative to the truck 9 during the transport from one place to another.

Having thus described our invention, what we claim as new and desire to secure by Letters-Patent, is:—

55. 1. An apparatus for loading centrifugal extractors having a rotary basket with a removable top rim, comprising in combination a bag for receiving and holding the charge, attached to the removable basket rim, conveying and lifting means for the rim and bag, a frame separate from the extractor adapted to support the rim and bag in a position ready for being filled with the material to be extracted, and means carrying the said frame so as to allow it to be turned 60 about its vertical central axis.

70. 2. An apparatus for loading centrifugal extractors having a rotary basket with a removable top rim, comprising in combination a bag for receiving and holding the charge attached by its upper end to the basket rim and provided at its lower end with means for closing and opening the same, a portable rotatable frame of substantially the same shape as the extractor basket adapted to receive and support the rim and bag in a 75 position ready to be filled with the material to

be extracted, a central cone-shaped projection extending from the bottom of the supporting frame inwardly of the same and adapted to have the central portion of the closed bottom of the bag seated on its summit when the bag is lowered into the supporting frame, and a conveying and lifting device for the rim and bag including suspension ropes adapted to be detachably fastened to the rim and a rope adapted to be detachably fastened to the bottom closing means and hold same in a predetermined position relative to the bag when same is withdrawn from the supporting frame and carried to and lowered into the extractor, substantially as described. 5

3. A means for loading centrifugal extractors through the use of a bag designed to be placed into and removed from the extractor basket and adapted to receive the extractor charge while outside the extractor basket, comprising a holding frame of substantially the same size and contour as the extractor basket, a material-receiving bag removably placed in said frame and completely shaped and sized by the frame to conform more or less exactly to the shape and size of the interior of the extractor basket, the bag 25 while exteriorly confined by the frame being in the exact size and shape assumed by the bag when in the extractor basket and being designed for loading with particular regard to quantity and load distribution, whereby the amount and distribution of the load in the bag while the bag is held in the frame will determine the distribution of the load, when placed in the basket, and elevating means connected to the bag for removing the bag from the frame and transferring it 30 to the basket, said elevating means being connected to the bag to maintain the frame-defining form of the bag and thereby the initial distribution of the load during transfer of the bag and its contents from the frame to the basket, 35 whereby during operation of the extractor on one load a subsequent load may be prepared therefor in exact accordance with load distribution desired when the load is within the basket to thereby materially reduce periods of inactivity of the extractor. 45

4. A means for loading centrifugal extractors, including a frame conforming in size and shape to that of the extractor basket, a bag removably supported in the frame and shaped in the frame 50 to conform to the size and shape of the extractor basket to permit loading the bag while in the frame in accordance with the desired relation of the load when the bag is in the basket, and means for transferring the loaded bag from the frame to the basket, said means being connected to the edge of the bag and to the central portion of the bottom thereof and arranged to maintain the form of the loaded bag when elevated from the frame in substantially exact accordance with the 55 form of the bag when in the frame, whereby when the loaded bag is transferred to the basket the relation of the load to the bag when the latter is in the frame will be maintained by the load in the bag when the latter is in the basket. 60

5. A method of providing a load of predetermined bulk and arrangement for the basket of a centrifugal extractor, with such load arranged wholly beyond the extractor basket and designed for bodily transference thereto, consisting in 70 providing a flexible container for the load, arranging and confining the entire container while wholly beyond the basket to compel the container to assume an exterior size and shape more or less exactly corresponding to the similar char- 75

acteristics of the extractor basket designed to receive the load, loading the container while confined as to size and shape beyond the extractor basket to insure a proper quantity and load distribution for the particular extractor basket, and transferring the loaded container from the point of loading to and within the extractor basket while maintaining during such transference the predetermined size and shape of the loaded container, whereby the load within the container when in the basket will have the same load characteristics as the load in the container outside the basket.

6. A method of providing a load preformed as to size, shape and load distribution to be placed within the basket of a centrifugal extractor in substantially exact preformed condition, consisting in providing a flexible load container adapted when in the basket to assume a size and shape

conforming to that of the basket, preforming the flexible container wholly beyond the basket into a size and shape substantially conforming to that of the basket, loading the container while in such preformed condition outside of the basket, with the load in the preformed container arranged and distributed to avoid centrifugal stresses when the load is within the basket, and transferring the preformed container with the load into the basket of the extractor while maintaining the preformed condition of the container and the load distribution of the load, whereby, while the extractor is operating on one load, a second load conforming in substantially exact correspondence to the size and shape of the basket and having a load distribution to avoid centrifugal stresses when in the basket may be made ready.
